(57) **CLAIM**

The ornamental design for a workstation as shown and described.

DESCRIPTION

FIG. 1 is a perspective view of a workstation according to a first embodiment of the claimed design, shown in a first configuration, a second embodiment of the claimed design in a first configuration consisting of a mirror-image thereof; FIG. 2 is a front elevation view thereof; FIG. 3 is a back elevation view thereof; FIG. 4 is a right side elevation view thereof; FIG. 5 is a left side elevation view thereof; FIG. 6 is a top plan view thereof; FIG. 7 is a bottom plan view thereof; FIG. 8 is a perspective view of the workstation according to the first embodiment of the claimed design, shown in a second configuration, the second embodiment of the claimed design in a second configuration consisting of a mirror-image thereof;

FIG. 9 is a front elevation view thereof; FIG. 10 is a back elevation view thereof; FIG. 11 is a right side elevation view thereof; FIG. 12 is a left side elevation view thereof; FIG. 13 is a top plan view thereof; and, FIG. 14 is a bottom plan view thereof.

The portions of the article shown in even broken line form no part of the claimed design.

The pairs of closely adjacent, spaced jagged broken lines and the portions therebetween, having been removed for clarity, form no part of the claimed design.

(Continued)

Dash-dot-dash broken lines represent the boundaries of the claim and form no part thereof.

1 Claim, 11 Drawing Sheets
